H. W. Beadle, Atty.

UNITED STATES PATENT OFFICE.

THOMAS ENNETT, OF ROCKFORD, ILLINOIS.

IMPROVEMENT IN LIMEKILNS.

Specification forming part of Letters Patent No. **104,291**, dated June 14, 1870.

To all whom it may concern:

Be it known that I, THOMAS ENNETT, of Rockford, in the county of Winnebago and State of Illinois, have invented a new and useful Improvement in Limekiln; and I do hereby declare that the following is a full and exact description of the same, reference being had to the accompanying drawing, and to the letters of reference marked thereon.

This invention relates to that class of limekilns which are called "perpetual burners;" and consists in certain details of construction, which will be fully described hereinafter.

In the drawing, Figure 1 represents a front elevation of the kiln, with a portion of one of its sides cut away to show the internal arrangement of the flues, and the grate and feeding-door; and Fig. 2 represents a top view, with a portion of the front side cut away to show the grates and draft-flues.

To enable others skilled in the art to make and use my invention, I will now proceed to describe fully its construction and method of operation.

A represents the kiln, which may be built of stone, brick, or other suitable material. It is provided with the four walls *a a a a*, which inclose the central space or cupola, *a'*, in the usual manner. These walls are constructed upon vertical straight lines, from a point in line with the lower edge of the grate-bars to the top of the kiln. From this point downward they are gradually drawn inward, in curving lines, until the bottom of the kiln is reached. This lower part of the cupola I call the "draw-pit."

By means of this construction it will be observed that the inclosed area at the bottom is much less than that at the top. These walls are, of course, provided with suitable fire-chambers and flues, as will now be described.

B B represent the fire-chambers, which are located upon each side of the cupola, as shown. They are provided with ash-pits *b b*, into which open flues *b¹ b¹ b²*, as shown in the drawings. They have also grates of suitable construction, which may be made of metal or brick, as may be desired. If brick be employed, they should, of course, be built upon the arches that support the grates, with openings corresponding to the openings in the arches. The grates in

either case, however, should be inclined, and should be made solid at the lower edges, for the purpose of holding the coals. By means of this construction, also, the expanding lime is prevented from pressing into the fire-chamber and ash-pits. The inner portion of the wall opposite the fire-chamber is, of course, made open, for the purpose of permitting the flame and smoke to pass up through the cupola. A single pillar, *c*, Fig. 2, is, however, employed to prevent the logs of wood fed to the fire from rolling into the cupola. By means of the inclined grates the wood rolls of its own accord down to the pillar, and is thus fed to the fire.

An additional chamber, corresponding to the ash-pits *b*, is located in rear of the lower part of the draw-pit of the cupola, with which communicates the flue *b²*. This chamber opens into the ash-pits, and can be used, if desired, for the purpose of increasing the draft. The flues and fire-chambers are, of course, provided with suitable doors.

d represents the door through which the finished lime is withdrawn, and *d'* a door through which the arch, which forms in the cupola, may be broken, either by an iron bar or by the introduction of a stream of water, in the usual manner.

The operation is as follows: The cupola is filled, from the top, with limestone, in the usual manner. Fires are lighted in the fire-chambers, and replenished, as may be necessary, by means of the feeding-doors. As the heat passes up through the stones, which lie loosely in the cupola, they become burned and fall into the draw-pit of the cupola in the form of lime. As the stones burn they naturally expand, and hence the upper part of the walls require great strength, and the grates require to be inclined to prevent the lime from passing into the fire-chamber.

In case an arch is formed by the expansion of the material in the process of combustion, an iron bar may be used at the door *d'*, or a stream of water may be introduced by means of a hose, in which case the steam consequently formed pulverizes the mass, and permits it to fall to the bottom of the kiln.

The ashes formed by the combustion of the wood fall through the grates into the ash-pits,

from which they may be drawn out by means of the communicating flues. The ash-pits, in connection with the chamber in rear of the collecting-chamber, serve also another purpose—that is, to cool the lime. By means of these the draw-pit is surrounded by currents of cool air, and the quality of the lime is thus prevented from being impaired by the excessive heat to which it would otherwise be necessarily exposed.

The form of the collecting-chamber is such that the lime is presented at the discharging-door in small quantities, adapted for ready removal.

By means of the different flues and chambers the draft can easily be regulated at will.

Having thus fully described my invention,

what I claim as new, and desire to secure by Letters Patent of the United States, is—

1. In the kiln herein described, the spaces *b*, extending from the grates to the bottom of the kiln, for the double purpose of withdrawing the ashes, &c., and for cooling the burnt lime.

2. The arrangement of the cupola *A*, with curved sides from the grate to the bottom, inclined grates, pillar *c*, air-space *b*, and doors *d b b¹ b²*, all constructed substantially as herein described, and for the purpose specified.

This specification signed and witnessed this 4th day of April, 1870.

THOMAS ENNETT.
